UNITED STATES PATENT OFFICE

153,933

DESIGN FOR A CHEST

James J. Gilmore, Sanford, N. C.

Application August 29, 1947, Serial No. 141,114

Term of patent 14 years

(Cl. D33—19)

To all whom it may concern:

Be it known that I, James J. Gilmore, a citizen of the United States, residing at Sanford, in the county of Lee and State of North Carolina, have invented a new, original, and ornamental Design for a Chest, of which the following is a specification, reference being had to the accompanying drawings, forming a part thereof.

Figure 1 is a front elevational view of a chest, showing my new design.

Figure 2 is an end view with the chest cover in a raised position.

Figure 3 is a front perspective view with a secondary cover in a raised position.

I claim:

The ornamental design for a chest, as shown.
JAMES J. GILMORE.
